(57) CLAIM

The ornamental design for a tombstone cigarette carrying case, as shown and described.

DESCRIPTION

FIG. 1 is a front view of the tombstone cigarette carrying case showing my new design;

FIG. 2 is a side view thereof;

FIG. 3 is a back view thereof;

FIG. 4 is a bottom view thereof;

FIG. 5 is a perspective view thereof; and,

FIG. 6 is an additional perspective view thereof.

The broken lines are shown for illustrative purposes only and form no part of the claimed design.
